UNITED STATES PATENT OFFICE.

GUSTAVE E. ERICKSON, OF MINNEAPOLIS, AND SELMER A. KRAFT, OF ST. PAUL, MINNESOTA; SAID KRAFT ASSIGNOR TO VICTOR BERGSTEDT, OF ST. PAUL, MINNESOTA.

LEVEL AND PLUMB.

Application filed October 2, 1926. Serial No. 139,076.

Our invention relates to a level and plumb device of the class commonly used in the building industry and the object is to provide an improved device of said kind which 5 is simple and efficient and eliminates the use of liquid in glass tubes.

In the accompanying drawing:

Fig. 1 is a top view of the central part of a level stock embodying our invention.

10 Fig. 2 is a partly sectional front elevation of Fig. 1.

Fig. 3 is a sectional detail view as on line 3—3 in Fig. 2.

Fig. 4 is an end elevation of our device on 15 line 4—4 in Fig. 2.

Fig. 5 is an enlarged sectional detail of the pivot mounting of our device on line 5—5 in Fig. 3.

Fig. 6 is a sectional elevation on line 6—6 20 in Figs. 1 and 4 showing mainly the brake or stop construction of our device.

Referring to the drawing by reference numerals, 10 designates the level stock usually consisting of an elongated straight bar of 25 suitable wood and laid with its lower edge 10^b on timbers either vertically or horizontally during construction work.

11 is a deep pocket or recess in the center of the stock and extending nearly to the bottom edge 10^b thereof, said pocket adapted to receive in its upper part a metal frame 12 with end flanges 12^c adapted to rest and be secured by screws 13 in depressions in the top edge of the block so that the entire top 30 of the frame 12 is flush with said top edge 10^c of the block (see Figs. 1 and 2). 12^a are side ears at the upper part of frame 12 preferably made flush with the sides of the block 10 and each having a window opening 14, and

35 another window opening 15 is provided in the upper face of the frame 12. 12^b are side walls of the frame formed integral with the ears 12^a and mainly below the latter, said walls 12^b being parallel and connected by end walls 12^c. 16 is an inverted U-shaped machined slot in frame 12 under its top and longitudinally thereof, to slidably receive and retain glass strips 17 in said U-formation and closing the window openings 14.

40 45 50 Between the lower frame members 12^b we mount a circular disc-wheel comprising a web 18, a hollow integral rim 18^a with suitable graduations on its opposite sides and corre-

sponding graduations on its periphery, the former readable through the side windows 55 14 at a so-called hairline H and the latter readable at a like line H in the top window 15. The disc wheel is mounted on a pivot pin 19 suitably fixed in the hub and its opposite ends pointed as 19^a, each point engaging in a concaved bearing member 20 of suitable hard material and imbedded in a hard rubber or other slightly yieldable material 21 in the form of a thimble frictionally retained concentrically in the threaded end of 60 a nut 22. These nuts are of course arranged to be screwed into horizontally registering threaded holes located in the lower central part of the walls 12^b and so located and adjusted that the disc-wheel graduations are 65 exposed in the windows 14 and 15. The wheel 18 must necessarily be very delicately balanced so as to be freely rotatable, its hollow rim containing a suitable heavy material 23 at one side of its center only so that when 70 the block 10 is absolutely level or vertical the reading at the hairline in all of the windows will be O. Any deviation from vertical or horizontal position of the level will of course be indicated in degrees at the hairlines H, 75 80 the weighted part of the disc wheel always remaining below center.

24 is a leaf-spring brake suitable fixed at one end to the under side of the upper wall or flange 12^c (see Figs. 1 and 6) its free end 85 24^a normally close to the perimeter of the disc wheel. Intermediate the ends of the spring a push button is fixed to it and projects upwardly through an aperture 26 in the top of frame 12 and accessible for pressure by a finger of the operator. Said button being pressed down the disc-wheel is of course engaged and prevented from turning. This feature is particularly useful for example when a carpenter uses the improved level at arms length over his head or in places where the light is poor and reading the angle must be done after moving the level from the timber on which it has been used.

In Fig. 5 is clearly shown that the pointed ends 19^a of the pivots 19 are engaged at the points only and the concave bearing end 22^a of the nut 22 is shallow so that the pointed or angular ends of the pivots do not touch the bearing. Thus in case the level is accidentally dropped or jarred suddenly the 100 105

pivot pins are less likely to become broken and the strain on the points is relieved by the yieldable material 21.

We claim:

- 5 In a level comprising an elongated bar with a central aperture and a longitudinally flanged indicator frame with its flanged parts secured flush with one edge of the bar, a rotary level indicator mounted in said frame, and the said bar having horizontal and vertical sight apertures; said rotary indicator consisting of a disc wheel with a central disc and an integral circular hollow ring quadrangular in cross section and a weight secured 10 in said ring to one side of its axis, said ring provided with corresponding indicia on its
- 15

sides and periphery and said windows having a radial stationary mark each outwardly of one of said indicating faces of the disc, and a brake for holding said disc wheel, said brake 20 comprising a leaf spring with one end fixed in the frame remote from the disc wheel and its free end, normally in proximity to the periphery of the disc wheel, a push button fixed on said spring and accessible exteriorly 25 of the frame for pressing said free end of the spring against the disc wheel.

In testimony whereof we affix our signatures.

GUSTAVE E. ERICKSON.
SELMER A. KRAFT.
